UNITED STATES PATENT OFFICE

FRANK M. ASHLEY, OF BROOKLYN, NEW YORK

FOUNTAIN PEN

Application filed May 31, 1930. Serial No. 457,991.

My invention relates to fountain pens of the self filling type in which a sack is used in filling the pen.

The object of my invention is to provide a self filling pen having the following features of novelty and utility.

First, a pen which may be made at a low cost, constructed with a soft rubber collapsible tube in open communication with a glass bottle which may be filled to serve as a part of the reservoir with the ink therein exposed to view.

Second, a pen having telescoping metal tubes, the outer one being exposed to view thru a translucent or transparent outer casing, and plated with gold, silver, or other colored material, or used without the outer casing, and exposed directly to the atmosphere for a portion of its length.

Third, a pen which may be made without the bottle feature, by substituting a rubber sack of the usual construction for the rubber tube shown in the drawing herewith submitted.

Fourth, a pen having the above features and constructed so that the reservoir portions of the pen may be easily separated from the casing portion without being disassembled as a reservoir unit.

Referring to the drawing which forms a part of this specification;

Fig. 1 is a longitudinal sectional view of a fountain pen embodying my invention.

Fig. 2 is a cross sectional view taken on line 2-2 of Figure 1, shown on an enlarged scale.

Fig. 3 is a perspective view of the glass bottle portion of the reservoir.

Fig. 4 is a view of the transparent end cap which covers the bottle portion.

Fig. 5 is an end view of the transparent end cap shown on an enlarged scale.

A— indicates the pen section, and B—a feed plug fitted therein, and provided with a small tube C—, the open adjacent end of which is in open communication with the feed-duct B'— by a small open passage C'— formed in the feed-plug.

The tube C— extends thru the reservoir

D— to a point adjacent the rear end thereof, as shown.

The pen section A— is reduced in diameter at E— to provide a surface over which an inner tube F— fits in frictional engagement and is readily removable therefrom. This tube is made from thin sheet metal by drawing dies, and presents a true smooth cylindrical outer surface over which the outer tube G— fits in close air tight sliding relation. The outer tube is made in the same manner as the inner tube, and its outer surface may be plated with any desired rich colored metal such as gold, or silver, or colored lac or enamel.

This outer tube G— may be made thick enough to serve as an outer casing, if desired, but I prefer to use a separate outer casing such as amber colored bakelite, or light colored cellulose material that is transparent, and to connect it to the pen section by a friction joint as illustrated at H'— the casing portion being indicated by H. The outer casing H— is separated from the outer tube G— by a very small space to prevent friction between the tube and inner wall of the casing. I— indicates a transparent or translucent end cap which is threaded to connect with the outer casing at I'— and is connected to the outer tube G— at the point J, so that the outer tube G— is movable with the end cap in the filling operation of the reservoir K. The end cap is provided with a hole I'— to serve as an air passage.

The inner end of the pen section is reduced in diameter to receive the open end of the soft rubber tube or sack L— which is fastened thereto in the usual manner, and the opposite end of the tube L— is connected to the open end of a glass bottle or tube M— by the use of shellac or other suitable means.

In case a pen is made without the bottle M— the tube L— is made longer to correspond with the length of the bottle, and its end closed, or in other words, a sack is substituted for the tube shown, and in this event the cap I— may be dispensed with if desired, and the telescoping tubes of metal and the outer casing tube of translucent material may be increased in length, to cover the sack, and the

outer tube G— may be allowed to extend beyond the casing H— to permit it to be grasped by the fingers during the filling operation.

5 It will be obvious to those skilled in the art to which this invention pertains, that many minor changes may be made in the construction of the parts, without departing from the invention disclosed, and I therefore 10 do not wish to be limited in the construction to the exact relative dimensions as shown.

The reservoir K— comprises the space within the pen section and within the rubber sack and bottle.

15 The pen is filled as follows:

Insert the end of the pen section beneath the surface of the ink in the ink receptacle, then unscrew the cap I— from the casing H— and withdraw the cap and outer tube G—

20 which is connected thereto, partway from the outer casing H—, then cover the hole I²— in the cap with a finger and reciprocate the cap slowly three or four times, and after the last outer stroke, remove the finger from the hole 25 I²— before the final inward stroke.

On the first outward stroke, air is drawn into the space between the cap and outer tube connected thereto, thru the hole I²— and trapped therein by covering the said hole with 30 the finger, and then compressed as the tube is forced inwardly, which acts to deflate the rubber sack L— and force the air from the reservoir thru the air tube C—, and on the outward stroke the air is rarefied which 35 causes the sack to expand and draw ink into the reservoir and be trapped therein. The function and construction of the air tube in fountain pens is well known to the art, and therefore requires no further description to 40 enable this pen to be properly made by those skilled in making fountain pens.

It will be understood that the tubes F— and G— are formed with very thin walls and take up very little space so that a sack of relatively 45 large diameter may be used.

The coloring of the barrel, protected by the outer casing from wear and from oxidation, provides an ornamental effect at a low cost.

50 The metal tubes may be lubricated to cause them to slide easily in air tight contact.

Since no moving part is exposed to the rubber sack, there is no danger of frictional engagement therewith in the filling operation.

55 Having thus described my invention I claim as new:

1. A fountain pen comprising a pen section, a feed-plug therein, a thin inner metallic tube connected to said pen section, a 60 thin metallic tube fitting over said inner tube the outer end of which is provided with an opening, a casing connected to said pen section and inclosing said outer tube, the adjacent faces of said tubes and casings being of 65 constant diameters throughout their contact-

ing lengths and a soft rubber sack in open communication with said feed-plug.

2. A fountain pen comprising a pen section, a feed-plug therein, a thin inner tube connected to said pen section, a thin tube fitting over said inner tube the outer end of which is provided with an opening, a casing connected to said pen section and inclosing said outer tube, the adjacent faces of said tubes and casings being of constant diameters throughout their contacting lengths, a soft rubber sack connected to said pen section, and an air tube connected to said feed-plug; the construction being such that by closing the end of the outer tube with a finger and reciprocating the tube, the air within said tube may be alternately compressed and rarefied to collapse and expand said soft rubber sack in the act of filling the pen.

3. A fountain pen comprising a pen section, a feed-plug therein, an inner tube connected to said pen section, a tube fitting over said inner tube, a casing connected to said pen section and in closing said outer tube, the adjacent faces of said tubes and casings being of constant diameters throughout their lengths, an end cap connected to said outer tube having a passage for air, and a soft rubber sack connected to said pen section.

4. The construction as set forth in claim 1; and having an air tube connected to said feed-plug which extends into and through the inner end of said sack and a transparent enclosure for the inner projecting end of the air tube.

5. A fountain pen comprising a pen section, a feed plug therein, an inner tube connected to said pen section, a tube having an ornamental color on its outer surface and fitting over said inner tube, a transparent or translucent casing inclosing said outer tube the adjacent faces of said tubes and casings being of constant diameters throughout their lengths.

In testimony whereof I have affixed my signature.

FRANK M. ASHLEY.
